PRESSING MACHINE

Philip G. Franklin, Liverpool, N. Y.

Application March 22, 1932, Serial No. 600,463

10 Claims.

(Cl. 38—34)

This invention relates to garment and laundry presses, and has for its object, a press which is manually and readily operable into final closed position with a minimum effort on the part of the operator and also, means for holding or bracing the carrier lever for the upper pressing element when the press is being closed under heavy pressure.

The invention consists in the novel features and in the combinations and constructions hereinafter set forth and claimed.

In describing this invention, reference is had to the accompanying drawings, in which like characters designate corresponding parts in all the views.

Figure 1 is a fragmentary plan view of this press.

Figure 2 is a side elevation, partly broken away, the parts being shown in their unlocked position after the final closing or pressing operation and before complete opening of the press.

Figure 3 is a view, similar to Figure 2, showing the position of the parts when in final closed, or pressing, position.

Figure 4 is an enlarged, fragmentary, detail view of the final clamping mechanism.

Figure 5 is a fragmentary detail view of the spring suspension means for the upper pressing element showing the spring compressed, or in its position assumed when the press is under heavy pressure.

This press is designed primarily as a household article, and the mechanism to be readily operated without fatiguing effort by the housewife or servant.

The press comprises generally, a suitable frame, cooperating pressing elements, one of which is movable toward and from the other, as upper and lower pressing elements, the latter being carried by the frame, a carrier for the movable, or upper pressing element, as a lever pivoted at or near its rear end to the frame in the rear of the pressing elements and extending forwardly and carrying the movable element at its front end, the movable element being yieldingly suspended from the front end of the carrier, and the lever being movable on its pivot to carry the upper pressing element into and out of a position opposed to, or over the lower pressing element, a bracing means, or lock, for holding the lever in its position assumed when the upper pressing element is opposed to the lower, means including an operating member for clamping the upper element into clamping coaction with the lower, and in so doing, moving it relatively to the carrier lever, and means

operated by the clamping mechanism for controlling the operation of the bracing means or lock.

1 designates the base of the frame, which is so constructed as to rest upon a bench or table. 2 5 is the lower pressing element mounted on the base by the usual goose neck, or pillar 3. 4 designates the upper pressing element or head, both pressing elements being of the platen type.

5 designates the carrier lever pivoted at 6 near 10 its rear end to upright brackets 7 rising from the base 1 of the frame, this lever extending forwardly from its pivot and having a support or head 8 at its front end from which the upper pressing element or head 4 is yieldingly suspended. 15 The lever 5 is movable on its pivot from the dotted line position shown in Figure 2 into the full line position to bring the upper pressing element 4 into a position over the lower pressing element 2, this movement being against the action of returning means, as a spring 9, housed within the frame 1 and anchored at its front end thereto and connected at 10 at its rear end to an angular arm 11 extending rearwardly from the lever 5.

The movable element 4 is yieldingly suspended 25 from the support or head 8 by means of studs 12 extending upwardly from the element 4 and through the head or support 8, and springs 13 thrusting against the heads of the studs in one 30 direction, and against the bottoms of sockets 14 formed in the head 8, through which sockets the studs extend.

The movable element 4 is clamped in finally 35 closed position by mechanism which is particularly easy to operate, so that the operation of the press will not strain or fatigue the operator.

This mechanism, as here shown, comprises a cam 16 mounted in the housing 17 rising from the support or head 8 and movable about its axis 40 by an operating lever 18 and motion transmitting parts operated by the cam and coacting with the head, this motion transmitting part being here shown as a follower or plunger 26 slidable vertically through the support or head 8 and co- 45 acting at one end with the cam 16 and thrusting at its other end against the movable element 4. The housing 17 is provided with a suitable cap 25. The lever 18 and cam 16 are mounted upon a rock shaft 27 extending transversely of the 50 tubular housing 17. The cam is provided with a lift portion which coacts with the follower or plunger 26 to depress it and with a flat or dwell portion 28 at the end of the lift portion in order to automatically lock the head 4 in its clamped 55

position, or in other words, so that the lever 18 will not return automatically to its upright position, when released, the cam thus locking the press in its finally closed position.

5 30 designates the bracing means, or lock, this being shown as pivoted at 31 in the brackets 7, and as movable on its pivot into and out of engagement with the lever 5, or an arm 32 extending rearwardly from the axis of the lever, this 10 arm 32 being provided with a removable wear piece 33 for coacting with the lock. The lock is here shown as acted upon by a spring 34 tending to move it into an operative position. The brace or lock 30, and the arm 32 or the wear piece 33 15 are shaped to coact with a cam action so that the brace or lock firmly locks in any position the pressing element 4 assumes when in finally closed position. The arm 32 and the brace or lock 30 are so arranged that when the press head 20 is pulled down, the brace or lock 30 is moved by its spring 34, under the arm 32 with a camming or wedging action, and thus holds the press closed, and the farther the head moves toward the lower pressing element 2, the farther the 25 brace or lock moves along the wear-piece or cam to take up the lost motion that would otherwise develop. In other words, the brace or lock has a follow-up action taking up all lost motion that would otherwise occur during the follow-up action, so that the cam 16, when operated by the 30 lever 18, delivers full pressure, and the pressure is not relieved by back action or back lash of the lever 4. It will be understood that the element 4 closes under final pressure to a degree determined 35 by the thickness of the work and the compression of the padding.

When the press is open and hence the carrier lever 5 elevated, the brace or lock 30 or upwardly extending arm thereof is held in its "out" position by the fact that it is thrusting against the 40 rear end of the rearward extending arm 32 of the carrier lever 5 and when the press is closed by pulling down on the handle 44, or bringing the press head into a position over the buck 2, the arm 32 is elevated permitting the lock 30 45 to be actuated by the spring 34 under the rear end of the arm 32 and thus hold the press closed; the lock 30 following up and coacting with the arm 32 with a camming action as the press is finally closed or tightened by the operation of the 50 lever 18.

The lock is controlled in its operation by connections operated by the lever 18. These connections are here shown as a link 35 slidable lengthwise of the lever 4 and connected at its front end 55 to a lever 40, and coacting at its rear end with an angular arm 36 on the brace or lock 30. The link 35 is controlled in its operation by the cam 16 and as here shown, the front end of the link 60 35 is connected to a lever 40 pivoted at 41 in the housing 17 adjacent the cam 16, and the cam and lever 40 have coacting parts or shoulders 42, 43 arranged to come into action when the lever 18 is 65 reversed to open the press. The shoulder 42 during retrograde or rearward movement of the lever 18 engages the shoulder 43 and thus by a camming action swings the lever 40 rearwardly to push the link 35 rearwardly against the arm 36 and rock the locking member 30 rearwardly or counterclockwise (Figure 3) out from 70 under the rear arm of the lever 4, so that the spring 9 is free to react on the carrier to fully open the press. The lever 40 and cam 16 are also provided with coacting stop shoulders to limit 75 the retrograde movement of the lever 18, after it

has been moved far enough to shift the locking member 30 out of its operative position, and as here shown, the cam is provided with a stop shoulder 46 coacting with a complementary stop shoulder 40^a on the lever 40. This coaction of the cam and the lever 40 is somewhat analogous to the action of two incomplete or mutilated gears normally out of mesh and brought into mesh so that one actuates the other and the rotation of the gears limited by the fact that the 10 intermeshing teeth of the incomplete gear come to the end of the play. The pressing element 4 is provided with a handle 44 on its front side. The lower element 2 is preferably supported on cushioning springs 45. Either one or both of the 15 elements 4 may be heated, as by electrical heating elements 46, Figure 3, and one or the other may be provided with the usual padding. Usually the upper element is heated and the heated element is provided with a projection 47 extending 20 outwardly therefrom over which articles can be drawn for ironing them. This projection 47 is analogous to a ruffle iron or puffed ball.

When the press is initially closed by pulling down the handle 44, due to lost motion between 25 the link 40 and the cam 16 or due to the strength of the spring 34 acting on the press or lock 30, the lock 30 shifts into locking engagement with the rearwardly extending arm 32 of the carrier lever 5 before the operator pulls forwardly on 30 the lever 18. Thus the press locks in its preliminarily closed position before the final pressure is applied, this action being due to the lost motion before referred to or to the strength of the 35 spring 34 being greater than the initial resistance of the lever 18.

In operation, when the press is open, the operator lays the work on the lower element 2, then closes the press by pulling down on the handle 44 with one hand, and clamps it into 40 final pressure position by pulling forward on the lever 18 with his other hand and moving it into the position shown in Figure 3. Owing to the comparatively large movement of the lever 18 and small incline of the cam 16, the upper 45 element 4 is moved into heavy pressure coaction with the lower element 2 with minimum effort on the part of the operator. When the operator pulls forwardly on the lever 18, the link 35 is free to move forwardly under the influence 50 of the spring 34 and the spring 34 moves the lock 30 under the arm 32 of the lever 5 and braces or locks the carrier lever 5 in closed position during the final clamping action of the cam 16. During this movement the shoulder 42 55 on the cam moves away from the shoulder 43 on the lever 40 (Figure 4). To open the press, the lever 18 is moved rearward to its full extent from its position shown in Figure 3, thus causing the shoulder 42 to coact with the shoulder 43 60 cam fashion and push the lock 30 out of its operative position permitting the spring 9 to react and swing the lever 5 upwardly to open the press. The stop shoulders 16^a and 40^a thereafter 65 come into engagement and limit the rearward movement of the lever 18.

What I claim is:

1. A pressing machine comprising a frame, upper and lower pressing elements, the lower element being mounted on the frame, the upper 70 element being movable toward and from the lower, a carrier for the upper pressing element comprising a lever pivoted to the frame, the lever being movable to carry the upper pressing element into and out of position over the 75

- lower pressing element, clamping means operable to move the upper pressing element relative to the lower into clamping engagement with the lower pressing element, means coacting with the 5 lever for bracing the lever during the clamping movement, and connections between the clamping means and the bracing means to control the movement of the bracing means into operative position during the clamping action, and to release the bracing means during the unclamping operation.
2. In a garment pressing machine, a frame, cooperating pressing elements, one being fixed to the frame, and the other movable toward and from the former, a support for the movable element including a lever pivoted to the frame and movable on its pivot to carry the movable element into and out of a position opposed to the other element, means acting on the lever tending to actuate it to open the press, clamping mechanism between the lever and the movable element for actuating the movable element, relatively to the lever, into clamping coaction with the other element, including an operating member, a lock for holding the lever in its position assumed when the press is closed, connections operated by said operating member for controlling the movement of the lock into operative position during the clamping action of said mechanism, and for moving the lock out of operative position during the unclamping action.
3. In a garment press, a frame, cooperative pressing elements, one being movable toward and from the other and the latter being carried by the frame, a carrier for the movable element, supported by the frame and movable to carry the movable element into and out of position opposed to the other element, means for moving the movable element relative to the carrier into and out of clamping coaction with the other element, said means including a support on the carrier, an oscillating operating lever mounted on the support and motion transmitting connections between the lever and the movable element, and locking means controlled by the operating lever for holding the carrier in its closed position, said locking means being controlled in its movement into locking position by the operating movement of the operating lever to clamp the movable element in final pressing position and out of operative position by a reverse movement of the lever.
4. In a garment press, a frame, cooperative pressing elements, one being movable toward and from the other and the latter being carried by the frame, a carrier for the movable element supported by the frame and movable to carry the movable element into and out of position opposed to the other element, means for moving the movable element relative to the carrier into and out of clamping coaction with the other element, said means including a support on the carrier, a cam mounted in the support to turn about a horizontal axis, motion transmitting means between the cam and the movable element including a follower coacting with the cam, an operating lever for turning the cam about its axis, means for locking the carrier in its closed position and means controlled by the cam for operating the locking means.
5. In a garment press, a frame, cooperative pressing elements, one being movable toward and from the other and the latter being carried by the frame, a carrier for the movable element supported by the frame and movable to carry the movable element into and out of position opposed to the other element, means for moving the movable element relative to the carrier into and out of clamping coaction with the other element, said means including a support on the carrier, a cam mounted in the support to turn about a horizontal axis, motion transmitting means between the cam and the movable element including a follower coacting with the cam, an operating lever for turning the cam about its axis, means for locking the carrier in its closed position and means controlled by the cam for operating the locking means.
6. In a garment press, a frame, cooperative pressing elements, one being movable toward and from the other and the latter being carried by the frame, a carrier for the movable element supported by the frame and movable to carry the movable element into and out of position opposed to the other element, means for moving the movable element relative to the carrier into and out of clamping coaction with the other element, said means including a support on the carrier, a cam mounted in the support to turn about a horizontal axis, motion transmitting means between the cam and the movable element including a follower coacting with the cam, an operating lever movable in one direction to turn the cam about its axis to close the press and in the opposite direction to open the press, means for locking the carrier in its closed position, and means controlled by the cam for operating the locking means including a lever pivoted to the support, connections between the lever and the locking member, the cam having a portion for coacting with the lever to operate the same, the lever and the cam having coacting parts for limiting the retrograde movement of the lever.
7. A pressing machine including a frame, upper and lower pressing elements, the lower element being mounted on the frame, the upper pressing element being movable toward and from the lower, a carrier lever for the upper pressing element, said lever being pivoted to the frame and having an arm extending on the opposite side of its axis to that on which the upper pressing element is located, the lever being movable to carry the upper pressing element into and out of position over the lower pressing element, clamping means operable to move the upper pressing element relatively to the lower into clamping engagement with the lower pressing element, a lock pivoted to the frame and having a part movable under said arm of the carrier lever to hold the carrier lever from retrograde movement, a spring acting on the lock to move it into operative position and connections between the clamping means and the locking means to control the movement of the locking means into operative position by its spring during the clamping action and to release the locking means during the unclamping operation.
8. A pressing machine including a frame, upper and lower pressing elements, the lower element being mounted on the frame, the upper pressing element being movable toward and from the lower, a carrier lever for the upper pressing element, said lever being pivoted to the frame and having an arm extending on the opposite side of its axis to that on which the upper pressing element is located, the lever being movable

to carry the upper pressing element into and out of position over the lower pressing element, clamping means operable to move the upper pressing element relatively to the lower into 5 clamping engagement with the lower pressing element, a lock pivoted to the frame and having a part movable under said arm of the carrier lever to hold the carrier lever from retrograde movement, a spring acting on the lock to move 10 it into operative position, and connections between the clamping means and the locking means to control the movement of the locking means into operative position by its spring during the clamping action and to release the locking means 15 during the unclamping operation, said arm and the locking means coacting with a camming action, whereby the locking means has a follow-up action.

9. A pressing machine including a frame, upper and lower pressing elements, the lower element being mounted on the frame, the upper pressing element being movable toward and from the lower, a carrier lever for the upper pressing element, said lever being pivoted to the frame, 25 the lever being movable to carry the upper pressing element into and out of position over the lower pressing element, clamping means operable to move the upper pressing element relatively to the lower into clamping engagement with the lower pressing element, a lock pivoted to the frame and having a part coacting with the carrier lever to hold the carrier lever from retrograde movement, a spring acting on the lock to move 30 it into operative position, the lock being normally held from movement by the carrier lever when the press is open and connections between the clamping means and the locking means 35

to control the movement thereof into operative position by the spring during the clamping action and to release the locking means during the unclamping action, said lever and lock having means coacting with a camming action whereby 5 the lock has a follow-up action.

10. A garment press including a frame, upper and lower pressing elements, the lower element being mounted on the frame and the upper pressing element being movable toward and from the lower, a carrier lever for the upper pressing element, said lever being pivoted to the frame and movable to carry the upper pressing element into and out of a position over the lower pressing element, a lock pivoted to the frame and having a part coacting with the carrier lever to hold the carrier lever from retrograde movement when the press is closed, a spring acting on the lock to move it into operative position, the lock having means normally coacting with the carrier 10 lever so that the carrier lever holds the lock from movement by its spring when the press is open and moves out of holding relation to the lock during downward movement of the lever to permit the lock to be moved by its spring into 15 locking engagement with the lever and hold the lever from retrograde movement, and means for moving the upper pressing element relatively to the lever into clamping coaction with the lower pressing element, including a lever movable in one direction to effect the clamping action and in the opposite direction to release the clamping action, and connections operated by the lever, when moved in a retrograde direction, to trip the lock. 25

PHILIP G. FRANKLIN. 30 35
